DESIGN FOR A STAND FOR BUSINESS MACHINES

Walter A. Anderson, Bridgeport, Conn., assignor
to Underwood Elliott Fisher Company, New
York, N. Y., a corporation of Delaware

Application November 2, 1936, Serial No. 65,643

Term of patent 14 years

To all whom it may concern:

Be it known that I, Walter A. Anderson, a citizen of the United States, residing at Bridgeport, in the county of Fairfield and State of Connecticut, have invented a new, original, and ornamental Design for a Stand for Business Machines, of which the following is a specification, reference being had to the accompanying drawing, forming part thereof.

The figure is a perspective view of a stand for business machines, showing my new design.

I claim:

The ornamental design for a stand for business machines, as shown.

WALTER A. ANDERSON.
